HOUSE HEATER

Harold H. Sykes, Grand Rapids, Mich.

Application May 14, 1934, Serial No. 725,600

4 Claims. (Cl. 126—90)

This invention relates to a novel construction of heater which may be used by itself for the heating of air or, preferably, in conjunction with the usual construction of warm air furnace, such 5 that a selected room or part of a house ordinarily supplied with heated air in severe cold weather by the furnace may be supplied with heated air from the heater during milder weather without the necessity of running the furnace.

10 The invention is for the purpose of producing an economically constructed and efficient heater in which the fuel used may be a gaseous or liquid fuel, the burning of which heats air very quickly and efficiently.

15 An understanding of the invention and the objects and advantages thereof may be had from the following description, taken in connection with the accompanying drawing, in which,

Fig. 1 is an elevation, with parts shown in section, illustrating the heater applied to the warm air pipe of a furnace installation.

Fig. 2 is an enlarged vertical section through the heater, and

Fig. 3 is a transverse section therethrough 25 showing the heater radiator in plan.

In the construction of the heater (see Fig. 2), a base plate 1 of substantially circular outline is shown, at the center of which is an upwardly projecting sleeve 2. Over this plate a radiator construction is located having vertical walls 3 joined with a horizontal top 4, the middle portion of which is pressed upwardly into a dome 5 in the sides of which are a large number of outwardly pressed flutes 6. This provides an enclosure between the plate 1 and the radiator thereover. A flat baffle plate 7 is secured to and around the sleeve 2 and extends outwardly toward but stops a distance short of the walls 3. It is located between the base plate 1 and the top 4 of the radiator.

The plate 1 at one side of sleeve 2 has an opening 8 therein, connected with which is a sheet metal conduit member 9 which, with the plate 1 and an extension 1a thereof, provides a passage leading from the burner chamber underneath the radiator to an outlet pipe 10 which is secured at its lower end to the outer extension 1a of the bottom plate 1.

50 A cylindrical housing having vertical walls 11 and a top 12 is placed over the radiator and secured at its lower edge portions thereto. This housing has an inlet at 13 for the entrance of cold air.

An elongated somewhat enlarged cylindrical sleeve 14 passes downwardly through the top 12

of the housing toward the radiating dome 5. Near its lower end it is flared outwardly to form a conical skirt 15 which extends partly over the radiating dome but is spaced therefrom as shown.

A burner 16 is located in the sleeve 2 and is supplied with fuel through a pipe 17. The fuel may be any suitable fuel such as either a gaseous or liquid fuel which will burn readily.

In operation of the burner as thus constructed, it is evident that the heat from the burner 16 will heat the radiating dome 5 and the fluted portions 10 thereof and also will heat the top 4, the products of combustion of the burning fuel necessarily flowing outwardly between the upper side of the baffle plate 7 and said top 4 of the radiator member, after which the products of combustion pass underneath the baffle plate and escape at the opening 8 through the conduit at 9 and thence to the outlet pipe 10.

20 Cold air entering the housing 11 through the inlet at 13 passes downwardly and is heated by the radiator with heated air rising through the outlet 14. The arrows indicate the direction of flow of the cold air inwardly at the inlet 13 and outwardly through the sleeve 14. This heater may be used by itself for heating a room or other enclosed space. It is of simple economical structure, all parts thereof being made of sheet metal except the burner and the pipe 17 leading thereto. The radiator transmits the heat from the burner to 25 the air quickly and efficiently.

25 This heater is particularly adapted to be used in conjunction with the warm air pipe of a warm air furnace. In Fig. 1 it is shown installed on a furnace pipe. The interior fuel burning structure 18, consisting of firepot, combustion chamber and radiator, is enclosed within an outer casing 19 to which a cold air pipe 20 leads from a register 21 installed in the floor 22 of a room. Cold air passing through this pipe to and inside the furnace casing 19 is heated and passes outwardly 30 through a warm air pipe 23 to a warm air register 24 so that the warm air is directed into the room.

35 In a warm air furnace pipe, such as indicated at 23, a damper 25 is usually mounted, or may be mounted across the same for controlling the amount of warm air which passes therethrough. With my installation of the heater of my invention on the warm air pipe 23, the outlet 14 for heated air is connected to the pipe 23 between the damper and the register 24. The inlet at 13 for cold air is connected to the pipe 23 between the furnace casing and the damper 25 as shown in Fig. 1.

40 With the damper 25 in a position to close the 50

55

pipe 23, that is, transversely across the same, cold air passing through the cold air pipe 20 to the furnace casing 19 may thence pass out through the pipe 23 to the inlet 13 to the outer casing 11 of the heater. Such air is heated and then passes outwardly through the outlet 14 to the pipe 23 at the opposite side of the damper 25 and thence to the room through the register at 24. The products of combustion from the pipe 10 may be led into the smoke pipe of the furnace.

This assembly, as shown in Fig. 1, provides a convenient way for heating a room normally supplied with hot air from the furnace through a furnace hot air pipe such as 23 at times when the weather is mild enough that the furnace as a whole should not be operated yet a limited amount of heat is desirable. Of course more than one of the outlet warm air pipes to the furnace may be supplied with the heaters as described. When the furnace is operated, the damper 25 is turned to horizontal position for the regular passage of air heated by the furnace.

The structure described is economical to produce and has a high efficiency in utilization of the heat produced by the burner and in transmitting it to air to be directed to the room which is to be heated.

The invention is defined in the appended claims and is to be considered comprehensive of all forms of structure coming within their scope.

I claim:

1. A heater comprising, a horizontal base having a central opening and an upwardly extending sleeve at said opening, a burner located in said sleeve, a horizontal baffle plate located around the sleeve and spaced from said base, a radiator having an upwardly extending dome portion over said burner and with sides extending from said dome to the outer edge portions of the base to form a closed chamber, said base having an outlet opening and a conduit connected therewith to carry away products of combustion, said baffle plate overlying the outlet opening in the base, and means for conducting heated air away from the radiator, said means comprising a pipe, the

inner end of which is flared outwardly to surround the upper portion of said dome and spaced a short distance therefrom, as specified.

2. A construction containing the elements in combination defined in claim 1, said dome having outwardly extending ribs or flutes to increase the radiating surface.

3. A heater comprising, a flat base having a central opening and a sleeve extending upwardly at said opening, a burner located in said sleeve, a radiating enclosing structure mounted on and above said base having a central upwardly extending dome, an outwardly extending horizontal top extending from the lower edges of said dome and downwardly turned sides connecting with the base, said base having a second opening therein, a conduit joined with said second opening for carrying away products of combustion, a horizontal baffle plate around the sleeve spaced from the base and said covering radiating structure, said baffle plate overlying the second opening, and a conduit having an upper cylindrical portion and a downwardly and outwardly flared conical lower portion into which the upper part of the dome extends, said conical portion of the conduit being spaced from the dome, as and for the purposes specified.

4. A heater comprising, a horizontal base having a central opening, a burner therein, a baffle plate connected adjacent the said central opening and spaced from and extending over the base, a radiator having an upwardly extending dome portion over said burner and with sides extending from said dome to the outer edge portions of the base to form a closed chamber, said base having an outlet opening and a conduit connected therewith to carry away products of combustion, said baffle plate overlying the outlet opening in the base, and means for conducting heated air away from the radiator, said means comprising a pipe, the lower end of which surrounds the upper portion of said dome and is spaced a short distance therefrom, as specified.

HAROLD H. SYKES.
